UNITED STATES PATENT OFFICE.

FRED G. KOPER, OF CHARLESTON, WEST VIRGINIA.

DOMESTIC-BOILER CIRCULATOR.

1,333,319.

Specification of Letters Patent.

Patented Mar. 9, 1920.

Application filed March 28, 1919. Serial No. 285,838.

To all whom it may concern:

Be it known that I, FRED G. KOPER, a citizen of the United States, residing at Charleston, in the county of Kanawha and State of West Virginia, have invented certain new and useful Improvements in Domestic-Boiler Circulators, of which the following is a specification.

The invention relates to means for providing hot water for domestic use and adapted more particularly for positively circulating the water in a domestic boiler so that economy results in the consumption of fuel and means is provided for readily removing sediment from the boiler.

The invention consists of a device adapted to be attached to the bottom of a boiler such as commonly used in connection with a kitchen range whereby to enable the water in the boiler to be heated in a manner so that hot water may be obtained in a comparatively short time after the heater is started and without requiring the heating of all the water in the boiler.

The drawings illustrate a preferred embodiment of the invention. However, it is to be understood that in adapting the same to meet different conditions, various changes in the form, proportion, and minor details of construction may be resorted to without departing from the nature of the invention as claimed hereinafter.

Referring to the drawings,

Figure 1 is a view in elevation of a domestic boiler provided with a water circulator embodying the invention, a portion of the lower part of the boiler being broken away to show more clearly the relation of the attachment.

Fig. 2 is a view on the line 2—2 of Fig. 1 looking upward, the part being shown on a larger scale.

Fig. 3 is a sectional detail on the line 3—3 of Fig. 2.

Fig. 4 is a modification adapted to form a stand for the boiler, the circulator, burner and boiler being in section.

Fig. 5 is a plan view of the modified form of circulator, a portion of the top being broken away.

Corresponding and like parts are referred to in the following description and indicated in the several views of the drawings by like reference characters.

The device is essentially a one-piece casting and comprises a hollow body 1 which is

of circular outline and comparatively shallow, the upper wall or top being convex and the lower wall or bottom concave, the two walls being spaced apart a short distance. The body 1 is provided with two nipples or collars 2 and 3 which are preferably internally threaded, the one to receive a pipe 4 and the other to receive a plug 5, whereby the nipple or collar 3 is closed. The pipe 4 is provided with a drain cock 6. The body 1 is provided centrally of its top with a tubular projection 7 which is threaded to receive a pipe 8. A passage 9 is provided at one side of the tubular projection 7 and establishes communication between the bottom of the boiler 10 and the top of the body 1. A baffle plate 11 is disposed within the body 1 about midway between the top and bottom thereof and its outer edge terminates within a short distance of the outer portion of the body. The baffle plate 11 is of concavo-convex form which corresponds to the outline of the top and bottom of the body 1. The baffle plate 11 communicates centrally with the tubular projection 7. The lower portion of the tubular projection 7 or that part adjacent the body 1 is enlarged and externally threaded, as indicated at 12 to make screw-thread connection with the threaded boss usually provided centrally of the bottom 13 of the boiler 10. When the device is in position the passage 9 constitutes a by-pass through the portion 12 so that the cold water may pass therethrough from the boiler 10 into the body 1, the hot water passing from the body 1 through the tubular projection 7 and pipe 8 into the boiler 10.

The bottom of kitchen boilers is usually of concavo-convex form and is disposed a short distance from the lower edge of the body of the boiler, thereby leaving a space. The present invention is designed to utilize this space, as clearly indicated in Figs. 1 and 3, the device being constructed so as to occupy the same, thereby confining the heat and utilizing the same to the best possible advantage. It is observed that sediment collecting in the outer portion of the body 1 may be drawn off through the pipe 4 by opening the drain cock 6. Upon removing the plug 5 a suitable instrument may be introduced through the nipple or collar 3 so as to scrape the interior of the device and remove any scale or other matter tending to collect on the walls of the body or baffle.

Figs. 1 and 2 indicate a heater 14 which may consist of a burner of any type for utilizing gas or liquid fuel. The heater or burner is disposed centrally below the circulator so as to utilize the heat to the best possible advantage. A pipe 15 extends into the boiler 10 to within a short distance of the bottom thereof and is connected with the main or other source of water supply. A pipe 16 connects with the top of the boiler and communicates with the hot water outlets. The pipe 8 terminates within the upper portion of the boiler. The water is supplied to the lower portion of the boiler. When the heater 15 is in operation the hot water from the circulator passes upwardly therefrom through the tubular projection 7 and pipe 8 into the upper portion of the boiler and the cold water from the boiler passes into the upper portion of the body 1 through the passage 9, thence around and beneath the baffle plate 11 and upwardly through the tubular projection 7. In this manner the water is rapidly heated in the upper portion of the boiler 25 and hot water may be obtained at any one of the outlets in a comparatively short time because it is not necessary to wait until all the water in the boiler 10 is heated, since the hot water from the upper portion of the boiler passes through the pipe 16 and out through the open outlet.

The foregoing description and the drawing have reference to what may be considered the preferred, or approved form of my invention. It is to be understood that I may make such changes in construction and arrangement and combination of parts, materials, dimensions, et cetera, as may prove expedient and fall within the scope of 40 the appended claim.

In the modification shown in Figs. 4 and 5 the circulator is constructed substantially in the manner hereinbefore set forth but is modified to adapt the same as a support for the boiler. A threaded boss 17 is formed 45 upon the lower side of the circulator at a central point and receives the upper end of a standard 18 which is provided with a foot or base 19. Lugs 20 project outwardly from the circulator and are internally threaded to receive screws 21 which engage the bottom 13 of the boiler and enable the latter to be plumbed. The circulator is strengthened by a plurality of ribs 22 which are formed on the top and extend radially thereof. Struts 23 connect the baffle 11 with the upper and lower walls of the device, thereby stiffening and strengthening the same and enabling it to sustain the weight of the boiler. The circulator operates in a manner substantially 50 as described herein.

Having thus fully described my invention, what I claim as new and desire to secure by Letters Patent is:—

A circulator, comprising a hollow shallow 65 circular body provided with offstanding apertured lugs, a depending central boss and a vertical projection containing two passages, the body being divided by a baffle, one of the passages connecting with the space 70 above the baffle and the other passage connecting with the space below the baffle, and set screws mounted in said apertured lugs.

In testimony whereof I affix my signature in presence of two witnesses.

FRED G. KOPER.
